SANITARY REFUSE CONTAINER

Filed May 20, 1927

Fig. 2.

INVENTOR,
Frank I. Gunnell.
By Martin P. Smith, a/cy.

UNITED STATES PATENT OFFICE.

FRANK I. GUNNELL, OF LOS ANGELES, CALIFORNIA.

SANITARY REFUSE CONTAINER.

Application filed May 20, 1927. Serial No. 192,849.

My invention relates to a sanitary refuse container and has for its principal object the provision of a relatively simple container that may be utilized as a cuspidor or as a 5 receiver for refuse in hospitals, sick rooms, in the offices, laboratories and workrooms of dentists, doctors and the like, or as a container for garbage.

Further objects of my invention are to 10 provide a refuse container of the character referred to that is relatively simple in construction, inexpensive of manufacture and which will be very effective in performing the functions for which it is intended.

Further objects of my invention are to 15 provide a sanitary refuse container having a hinged cover that may be readily manipulated when opened or closed and which will, by gravity, retain its open position and to 20 provide the container with a sanitary moisture proof lining which may be readily removed from the main body of the container, thereby enabling the used lining and its contents to be destroyed by being burned in an 25 incinerator or the like.

With the foregoing and other objects in view, my invention consists in certain novel features of construction and arrangement of parts that will hereinafter be more fully described and claimed and illustrated in the 30 accompanying drawing, in which—

Fig. 1 is a perspective view of a refuse container constructed in accordance with my invention.

Fig. 2 is a vertical section taken on the line 2—2 of Fig. 1.

Fig. 3 is a section similar to Fig. 2 and showing a modified form of the hinge connection between the lid or cover of the receptacle and the body thereof.

Referring by numerals to the accompanying drawings which illustrate a practical embodiment of my invention, 10 designates a container that is preferably formed from 45 a single piece of suitable sheet metal and which container may be of any desired size, and connected by a hinge 11 to the upper portion of the side wall of the body of the container is a disk 12, preferably of sheet metal that serves as a cover for the container.

The diameter of the covering member 12 is slightly greater than that of the body of the container and thus when the cover is

properly positioned on said container, its 55 marginal portion projects a slight distance beyond the upper edge of the wall of the container body.

One plate of the hinge 11 is secured in any suitable manner to the underside of the cover 60 12 while the other plate of said hinge is connected to the wall of the container body 10 and the pin that connects the two plates of the hinge is arranged so that it occupies a position a short distance away from the wall 65 of the container and thus when the cover is swung into an open position, it will swing outwardly "past center" into the position shown by dotted lines in Fig. 2, and thus by gravity retain its open position. 70

Fixed in any suitable manner to the top of cover plate 10 and preferably directly above the hinge 11, is a short outwardly projecting arm 13, preferably formed of metal, the outer end of which is turned upward to 75 form an ear or lip 14. This arm 13 provides an extension that may be readily engaged by the foot and pressed downward to open the cover and when it is desired to close the cover, a slight inward pressure of the foot 80 against the upper end of said cover will swing the same inwardly "past center" and thus the cover will, by gravity, swing downward into closed position.

The removable lining for the container 85 comprises a section 15 of suitable thin moisture-proof material, for instance paper that has been treated with paraffin or a suitable oleaginous material, and this lining member is formed so that it will fit snugly within the 90 body of the container 10 and when so positioned therein, the upper edge of the wall of said lining extends a short distance outwardly so as to overlie the upper edge of the wall of the container. Thus the overlying 95 edge of the lining member 15 functions as a packing between the top of the body of the container and the cover thereof, as well as a silencer to prevent undue noise when the cover 12 swings downward into position to 100 close the container.

Arranged within the moisture-proof lining member 15, is an absorbent lining 16 of suitable fibrous material, for instance cotton that has been chemically treated to render it 105 fire-proof and which is also treated so as to render it thoroughly antiseptic.

To render the fibrous lining 16 antiseptic,

I prefer to treat it with a germicidal agent or solution and preferably one that will tend to absorb or eliminate noxious vapors.

The absorbent fibrous lining 16 may be secured to the moisture-proof lining 15, thereby enabling the two linings to be rendered as a single element while being placed in or removed from the container 10, or the two parts of the lining may be unattached so as to be separately handled.

In the use of my improved sanitary refuse container, the linings 15 and 16 are positioned within the container 10 and when it is desired to place refuse within the container, pressure of the foot on the outer end of arm 13 elevates the cover 12, thereby opening the container and permitting refuse to be placed or discharged thereinto. The absorbent fibrous lining 16 will readily absorb any liquid that forms a part of the refuse placed in the container and the treating of said fibrous lining to render the same fire-proof prevents said lining from burning in the event that a lighted match is thrown into the container.

The moisture-proof lining 15 prevents moisture from making contact with the inner surface of the container and when it is desired to remove the lining and the waste material deposited thereinto, the overlying edges of the outer member 15 of the lining are engaged and drawn together after the manner of closing the mouth of a paper bag and said lining with its contents may now be destroyed, preferably by burning in an incinerator or the like.

In the modified construction illustrated in Fig. 3, the arm 13 is dispensed with and a portion of the cover plate is extended outward a short distance to form a short arm such as 13^a and where such construction is employed, the upper plate of the hinge is

secured directly to the underside of said arm 13^a.

Thus it will be seen that I have provided a relatively simple and practical container that may be advantageously employed as a cuspidor, a garbage can, as a receiver for waste or refuse material in operating rooms, doctors' and dentists' offices and which container is provided with a readily removable lining that is treated so as to render it sanitary as well as fire-proof and which lining, together with the waste material and refuse that has been placed in the container, may be readily disposed of.

It will be understood that minor changes in the size, form and construction of the various parts of my improved sanitary refuse container may be made and substituted for those herein shown and described without departing from the spirit of my invention, the scope of which is set forth in the appended claims.

I claim as my invention:

1. A sanitary refuse container comprising a receptacle, a hinged cover therefor, a two-part lining removably positioned within said receptacle and covering the entire inner surface thereof, one of the parts of said lining being formed of moisture-proof material and the other part of fibrous fire-proof anti-septic absorbent material and the edge of which two-part lining overlies the upper edge of the receptacle.

2. The combination with a receptacle, of a lining of flexible moisture-proof material removably positioned within said receptacle and a lining of absorbent fire-proof material carried by said first mentioned lining which two linings entirely cover the inner surface of said receptacle.

In testimony whereof I affix my signature.
FRANK I. GUNNELL.
